PULVERIZER MILL

Harry R. Collins, Allentown, Pa.; May H. Collins
administratrix of said Harry R. Collins, deceased

Application August 12, 1936, Serial No. 95,658

18 Claims. (Cl. 83—45)

This invention relates to pulverizer mills especially intended for the reduction of non-metallic materials, such as coal, limestones, and cement clinker, by either wet or dry grinding, and in its more specific aspects pertains to mills of the type in which the grinding assembly preferably comprises a plurality of annular series of grinding elements, such as balls, which cooperate with grinding surfaces, one of which is rotatably driven in a horizontal plane to actuate the balls.

Among the objects of the present invention may be noted the provision of a mill of simple mechanical construction in which reduction of the material under treatment is accomplished in a plurality of stages, the structure contemplating an arrangement in which a grinding assembly of the stated character and the driving mechanism therefor are symmetrically disposed about a vertical axis with the driving mechanism being positioned above the grinding assembly. Further, the driving and grinding mechanisms are arranged as separate assemblies, independently supported and self-centering, with the contemplated arrangement permitting assembly, installation, and/or removal of the driving mechanism as a unit without disturbing the grinding assembly, which latter, upon removal of the driving mechanism as aforesaid, is readily accessible and removable so that elements thereof subjected to wear may be expeditiously replaced when necessary.

The present invention further contemplates a pulverizer mill of the above character in which the weight of certain parts of the grinding assembly is carried by the grinding elements, thus to apply grinding pressure thereto, and in which the grinding pressure may be further adjusted to the material under treatment in a simple manner and by readily accessible means, with provision being made for the regulation of the degree of fineness of the product to satisfy varying requirements.

Other objects will be in part obvious and in part hereinafter pointed out in connection with the accompanying drawings illustrating two embodiments of the invention in detail.

In these drawings, wherein like reference characters designate like parts throughout the several figures,

Fig. 1 is an elevation, partly in section, of a pulverizer mill in accordance with one embodiment of the invention,

Fig. 2 is an elevation, partly in section, of a modified construction in accordance with the invention, and

Fig. 3 is a broken away detail of certain parts thereof.

Referring to the drawings, and more particularly to Fig. 1, reference character 10 designates a generally cylindrical casing constituted by a lower casing section 11, provided with an annular flange 12 which may serve as a bed plate for the apparatus, and an upper section 13. Between the casing sections 11 and 13 is arranged a main bearing support 14, with bolts or equivalent securing means 15 removably securing the bearing support 14 to facing flanges of the aforesaid casing sections. The upper casing section 13 is provided with a horizontal top plate 18 which serves to close the top of the casing 10 as formed by the casing section aforesaid.

Arranged on the top plate 18 of casing section 13 and suitably secured thereto is a vertically disposed motor 20 for the driving assembly, the motor shaft 21 of which extends through the top plate 18 and into a chamber or compartment formed by the casing section 13, its top plate 18, and the main bearing plate 14.

This motor shaft 21 carries a hardened steel pinion 22 which drives oppositely arranged idler gears 23, 24 carried by bearings on suitable vertical shafts 25, 26, respectively, secured in the cover plate 18 of the top casing section. Idler gears 23, 24 mesh with a ring gear 28 carried by a circular supporting plate 30, the latter being secured as by bolts 31 to a flange formed on the upper end of the main driving shaft 32, the upper portion of which is circular in cross-section.

The main bearing plate 14 is provided with a central elongated hub 33 disposed about the circular portion of the shaft 32, the hub being suitably recessed to receive the outer raceways of spaced roller bearings 34, 35, the inner raceways being carried by the main driving shaft 32. Said bearings are suitably lubricated as by grease injected through a bore (not shown) in the main bearing plate 14. A packing ring 36 operative between the lower end of the plate hub 33 and the driving shaft 32 serves to exclude entry of dust along the shaft into the bearings and driving mechanism.

Main bearing plate hub 33 extends upwardly above the top horizontal surface of the main bearing plate 14, and hence there is formed within the compartment housing the driving assembly as aforesaid an annular well or primary reservoir adapted to contain a quantity of lubricating oil for the elements of the driving assembly, such being supplied to the reservoir through a port 40 55

in bearing plate 14 and communicating with an oil supply line indicated at 41.

The bottom plate 30 of the ring gear 28 is provided with one or more apertures as at 42, 5 and threaded into each of said apertures is a scoop pipe 43 which extends downwardly into the oil reservoir and below the level of the oil contained therein. Upon rotation of the ring gear 28 and its bottom plate, the open-ended 10 scoop pipes 43 pick up oil contained in the reservoir and force it upwardly into a secondary reservoir in the zone of the motor shaft pinion 22, idler gears 23, 24, and gear surfaces of the ring gear 28, thus to lubricate the same.

15 Vertical shaft 25 on which idler gear 23 rotates extends through the top plate 18 of casing section 13, and into a two-part housing 45 suitably secured to the casing top plate, the housing 45 containing drive elements for a rotating feed 20 table 46.

The feed table driving mechanism preferably consists of a worm pinion 47 keyed or otherwise secured to the upper end of the vertical shaft 25, the pinion being in driving relation to a gear 25 (not shown) arranged on horizontal shaft 48 suitably journaled in the housing 45, and being provided also with a worm gear surface (not shown) in driving relation to a pinion 50 carried by vertical feed table shaft 51. Idler shaft 25, 30 the horizontal shaft 48, and the feed table shaft 51 are suitably mounted in bearings as illustrated, the arrangement being such that feed table 46 is driven from the motor shaft 21 through a gear train including pinion 22, idler gear 23, pinions 35 47 and 50, and the gears on shaft 48.

To lubricate the driving parts contained in housing 45, the top plate 18 of the casing section 13 and the bottom wall of housing 45 are provided with a set of aligned apertures and threaded into said apertures is a scoop pipe 52 (shown in dotted lines), the lower open end of which extends into the cavity formed by ring gear 28 and its bottom plate 30, and below the level of the idler gear 23 rotating on a fixed axis therein. 40 Hence, oil forced into the ring gear 28 by scoop pipe 43 is in turn raised by scoop pipe 52 into the housing 45, and functions to lubricate the driving elements therein contained.

The lower end of the main shaft 32 is of square 50 or other angular section and extends through a central opening in the hub portion of a rotary grinding ring 55, which opening is slightly larger than the shaft, whereby the ring is permitted a limited free vertical as well as horizontal movement to maintain alignment to accommodate possible inaccuracies in manufacture or normal wear of the grinding elements. The grinding ring 55 is provided with an intermediate portion which is substantially conical and with a horizontal rim 55 portion suitably recessed on its upper side to receive a circumferentially channeled raceway 56 which is welded or otherwise secured to the ring. Supported on the raceway 56 is an upper annular series of grinding balls 57, the top portions 60 of which engage in a circumferentially grooved raceway 58 welded or otherwise secured to the under surface of a non-rotating grinding ring 60. The upper surface of the non-rotating ring 60 is inclined inwardly and along its periphery 70 is provided with a plurality of spaced spring pockets which open upwardly, with the bottom wall of each pocket being apertured to receive a spring-carrying bolt 62, on which is arranged a compression spring 63 operating between the bottom of the spring pocket and a collar 64 located

on the compression bolt by the holding and locking nut assembly designated 65. The said compression bolts at their lower ends are threaded into a shelf ring 66 which seats on an inwardly directed shelf or ledge 67 formed on the inner 5 wall of the casing section 11.

In the above described arrangement the non-rotating grinding or pressure ring 60, the upper grinding surface 56 of the rotating ring 55, and the annular series of grinding balls 57 constitute an upper grinding stage, in which material to be pulverized is directed to the inner side of the grinding balls by the inclined upper surface of the non-rotating ring 60 and the conical upper surface of the rotating ring 55. It will be further seen that the weight of the non-rotating grinding ring 60 of this upper stage is carried by the grinding balls 57, thus to apply grinding pressure thereto. This grinding pressure may be supplemented by the action of the compression springs 20 63 operating through the non-rotating pressure ring 60. The nuts 65 provide a simple means of adjusting the grinding pressure to that desired.

The upper non-rotating ring 60 is permitted limited vertical movement but is held against rotational movement, as by two or more oppositely arranged keys 68 (Fig. 3) formed on the inner wall of the casing section 11 and engaging in vertical slots or ways 69 formed in the periphery of the non-rotating ring.

The lower grinding stage is preferably constituted by a circumferentially grooved raceway 70 welded or otherwise secured to the under rim portion of the rotating ring 55, which engages the top portions of a second or lower series of 35 grinding balls 72 supported on a circumferentially grooved raceway 73 welded or otherwise secured to a bottom fixed ring 74. The arrangement is such that both series of balls are vertically aligned and the upper grinding surface of each 40 stage is directly above the lower grinding surface thereof. Hence, grinding pressures are applied in a vertical, downward direction.

The bottom fixed ring 74 of the lower grinding stage is welded or otherwise secured along its 45 peripheral edge to a cylindrical plate ring 75 which is disposed within and spaced from the casing section 11, and has its upper end welded or otherwise secured to the fixed ring 66. Thus, the fixed ring 74 of the lower grinding stage is 50 supported from the shelf ring 67, and in turn supports the upper and lower series of grinding balls, upper grinding ring 60, and rotary grinding ring 55.

Fixed shelf ring 66 is removably secured on 55 its supporting shelf as by holding bolts 76 which extend through thickened portions of the casing section 11 and bear downwardly on the ring, thus to securely maintain it seated on the shelf 60 77. When it is desired to remove the ring 66 and the entire grinding assembly carried thereby as in the foregoing, holding bolts 76 are unthreaded, and raising bolts 77, operating through the casing wall against the under face of the ring, function to unseat the ring 66 from the shelf 67, whereupon the said ring and parts carried thereby may be raised for removal from the casing.

The material is discharged from the upper 70 grinding stage through an inclined screen 78 carried by the rotary ring 55 and arranged adjacent the outer side of the grinding balls 57. The material thence drops downwardly to the annular space inwardly of the cylindrical plate ring 75 and is directed to the outer side of the lower grinding 75

balls 72. Following suitable treatment in the lower stage, the pulverized material is discharged from the inner side of the balls 72, under the control of an adjustable height dam 79 and screen 80 secured in suitable manner to the inner edge of the fixed grinding ring 14. The material is thereupon picked up by air entering the casing through an air inlet opening 81 in the lower portion of casing section 11 to a fan 82. After passing through a suitable grating 83, the pulverized material enters the fan, by which it is forwarded as desired.

The fan 82 is preferably driven by a shaft 84 which passes upwardly through a bore 85 in the main driving shaft 32 and is secured to the hub of the driving pinion 22. The lower end of the shaft 84 is supported for rotation in a bearing (not shown) formed in the lower fan section. It will thus be seen that the motor drives the fan 82 at full load speed, whereas the grinding balls of both grinding stages are driven circumferentially of the mill at a speed which preferably corresponds to the gravity fall of the material, through the speed reducing effect of the driving mechanism as aforesaid.

It will be understood that a slurry pump will be substituted for the fan 82 when wet grinding is contemplated.

Considering now the modification illustrated in Fig. 2, the driving mechanism is preferably substantially the same as above described. The rotating grinding ring 55 is driven from the driving shaft 32 and the grinding assembly comprises an upper stage consisting of an upper series of grinding balls 57 operative between circumferentially channelled raceways 56 and 58 carried, respectively, on the upper surface of the rotating ring and the under surface of the non-rotating pressure ring 60, all as aforesaid; and a lower stage consisting of a lower annular series of grinding balls 72 operating between raceways one of which, 70, is carried on the under side of the rotating grinding ring 55 and the other, 73, is seated on the upper side of a fixed grinding ring 74A, the relatively outer edge of which is formed with an overhanging flange 74B which seats on an inwardly directed shelf or ledge 12A formed on the casing bed plate 12.

Spring-carrying bolts 62A extend through the non-rotating pressure ring 60 as previously described, and their lower ends extend through aligned apertures formed in the overhanging flange 74B of the bottom grinding ring and the inward flange 12A of the bed plate 12. Bolts 62A are each provided with an expanded collar 62B arranged to bear against the top face of overhanging flange 74B so that, by tightening up the lower nuts 62C, the collars 62B are drawn tight against the overhanging flange and serve not only to removably secure the fixed bottom ring 74A to the casing, but also to anchor the lower ends of the compression bolts 62A.

To remove the lower fixed ring 74A and the entire grinding assembly carried thereby, certain of the expanded collars 62B engage beneath forked clamps 62D bolted or otherwise secured to the overhanging flange of the said lower ring. The arrangement is such that, upon unthreading the lower tightening nuts 62C, the forked clamps secure the lower fixed ring 74A to the expanded collars whereby said ring and parts carried thereby may be lifted bodily by the compression bolts 62A.

The path of material flow in both the Figs. 1 and 2 constructions is similar, the material entering the casing in regulated quantity through spout

90 under the control of the work feed table 46 previously described. The inclined surfaces of the top pressure ring 60 and the rotating intermediate ring 55 thereupon direct the material to the inner side of the grinding balls of the upper 5 grinding stage, being discharged therefrom through the screen 78, and falling to the outer side of the grinding balls 72 of the lower grinding stage, from which it is controllably discharged as by the adjustable height dam 79 and associated 10 screen 80 as previously described.

In the Fig. 2 construction, an exhaust fan 82A is suitably secured to the under side of the casing or bed plate thereof, the air entering thereto through the inlet openings 81A at the bottom of the casing, with the inlet air in the present modification being drawn directly through the grinding balls of the lower stage and screen, thus to assist in the discharge of the finished product.

In pulverizer mills according to the foregoing, 20 the symmetrically disposed driving and grinding mechanisms are separate assemblies. Thus, by removal of the holding bolts 15, top casing section 13 may be lifted, thus to permit access to the driving mechanism supported by the main bearing plate 14, and, further, by raising the main bearing plate 14, the complete driving assembly may be removed from the casing to permit access to the grinding assembly or to permit removal of the latter for the purpose of replacing worn parts. 30

Further, by the unique grinding assembly of the present invention, grinding pressures can be adjusted to the material under treatment, with the dams 79 on the outlet side of the lower annular series of grinding balls acting to control the degree 35 of fineness of the material passing through screens 80. Accordingly, particle sizes can be closely controlled, and the resulting product will be substantially uniform in size. The disposition of compression bolts and springs within the casing and 40 outwardly of the grinding balls further aids in the free flow of the material through the mill, and represents simplified constructional and design features.

As many changes could be made in carrying 45 out the above construction without departing from the scope of the invention, it is maintained that all matter contained in the above description or shown in the accompanying drawings shall be interpreted as illustrative and not in a 50 limiting sense.

I claim:

1. A pulverizer mill comprising, in combination, a casing, upper and lower non-rotating grinding rings, an intermediate rotating ring, 55 upper and lower annular series of grinding elements disposed between and engaging respectively the upper and intermediate rings and the intermediate and lower rings, a shelf ring removably supported within said casing and disposed 60 about the grinding elements, means carried wholly by said shelf ring and operative to exert grinding pressure on said grinding elements, means suspending the lower grinding ring from the shelf ring, and means for driving the rotating 65 ring.

2. A pulverizer mill comprising, in combination, a casing, upper and lower non-rotating grinding rings, an intermediate rotating ring, 70 upper and lower annular series of grinding elements disposed between and engaging respectively the upper and intermediate rings and the intermediate and lower rings, a shelf ring removably supported within the casing and arranged 75 about the grinding elements, spring means car-

ried wholly by the shelf ring and operative through the upper ring to exert grinding pressure on the grinding elements, means suspending the lower grinding ring from the shelf ring, and 5 means for driving the rotating ring.

3. A pulverizer mill comprising, in combination, a casing, upper and lower non-rotating grinding rings, an intermediate rotating ring, upper and lower annular series of grinding elements disposed between and engaging respectively the upper and intermediate rings and the intermediate and lower rings, a shelf ring removably supported within the casing and arranged about the grinding elements, spring means for 10 exerting grinding pressure on the grinding elements, said means comprising compression bolts anchored in said shelf ring, compression springs arranged on said bolts and operative against the upper ring, means suspending the lower ring from 15 the shelf ring, and means for driving the rotating ring.

4. A pulverizer mill comprising, in combination, a casing, upper and lower non-rotating grinding rings, an intermediate rotating ring, 20 upper and lower annular series of grinding elements disposed between and engaging respectively the upper and intermediate rings and the intermediate and lower rings, a shelf ring removably supported within said casing and disposed 25 about the grinding elements, means carried wholly by said shelf ring and operative to exert grinding pressure on said grinding elements, a downwardly extending plate ring carried by the shelf ring, the lower ring being secured to the 30 plate ring, and means for driving the rotating ring.

5. A pulverizer mill comprising, in combination, a casing, upper and lower non-rotating grinding rings, an intermediate rotating ring, upper and lower annular series of grinding elements disposed between and engaging respectively the upper and intermediate rings and the intermediate and lower rings, a shelf ring removably supported within the casing and arranged about the grinding elements, spring 40 means carried wholly by the shelf ring and operative through the upper ring to exert grinding pressure on the grinding elements, a downwardly extending plate ring carried by the shelf ring, the lower ring being secured to the plate ring, and means for driving the rotating ring.

6. A pulverizer mill comprising, in combination, a casing, upper and lower non-rotating grinding rings, an intermediate rotating ring, upper and lower annular series of grinding elements disposed between and engaging respectively the upper and intermediate rings and the intermediate and lower rings, a shelf ring removably supported within said casing and arranged about 50 the grinding elements, spring means for exerting grinding pressure on the grinding elements, said means comprising bolts anchored in the shelf ring, and compression springs arranged on said bolts and operative against the ring, a downwardly extending plate ring carried by the shelf, the lower ring being secured to the plate ring, and means for driving the rotating ring.

7. A pulverizer mill comprising, in combination, a casing, upper and lower non-rotating grinding rings, an intermediate rotating ring, upper and lower annular series of grinding elements disposed between and engaging respectively the upper and intermediate rings and the intermediate and lower rings, a shelf ring removably supported within said casing and disposed 60

about the grinding elements, means carried by said shelf ring and operative to exert grinding pressure on said grinding elements, a downwardly extending plate ring carried by the shelf ring, the lower ring being secured to the plate ring inwardly thereof, the plate ring being spaced from the casing whereby to provide an annular passage, and means for driving the rotating ring. 5

8. A pulverizer mill comprising, in combination a casing, a grinding assembly including upper and lower non-rotating grinding rings, an intermediate rotating ring, upper and lower annular series of grinding elements disposed between and engaging respectively the upper and intermediate rings and the intermediate and lower rings, the casing including a bed plate, cooperating means on the bed plate and the lower ring for supporting the lower ring, means arranged wholly within the casing and outwardly of the grinding elements for exerting grinding pressure 10 thereon, said means also providing a connection between the non-rotating rings whereby the grinding assembly may be raised bodily from the casing, and means for driving said rotating ring. 15

9. A pulverizer mill comprising, in combination, a casing, a grinding assembly including upper and lower non-rotating grinding rings, an intermediate rotating ring, upper and lower annular series of grinding elements disposed between and engaging respectively the upper and intermediate rings and the intermediate and lower rings, the casing including a bed plate having an extension projecting into the casing, the lower ring being supported on said extension, means arranged wholly within the casing and outwardly of the grinding elements for exerting grinding pressure 20 thereon, said means also providing a connection between the non-rotating rings whereby the grinding assembly may be raised bodily from the casing, and means for driving the rotating ring. 25

10. A pulverizer mill comprising, in combination, a casing, a grinding assembly including upper and lower non-rotating grinding rings, an intermediate rotating ring, upper and lower annular series of grinding elements disposed between and engaging respectively the upper and intermediate rings and the intermediate and lower rings, the casing including a bed plate having a flange extending into the casing, the lower ring having an overhanging flange seating on the bed plate flange, means arranged wholly within the casing and outwardly of the grinding elements for exerting grinding pressure thereon, said means also providing a connection between the non-rotating rings whereby the grinding assembly may be raised bodily from the casing, and means for driving the rotating ring. 30

11. A pulverizer mill comprising, in combination, a casing, upper and lower non-rotating grinding rings, an intermediate rotating ring, upper and lower annular series of grinding elements disposed between and engaging respectively the upper and intermediate rings and the intermediate and lower rings, the casing including a bed plate having a flange extending inwardly of the casing, bolts removably anchored in said flange and extending upwardly through said upper ring and outwardly of the grinding elements, said bolts providing a connection between the non-rotating rings, compression springs arranged on the bolts and operative against the upper grinding ring, and means for driving the rotating ring. 40

12. A pulverizer mill comprising, in combina- 45

tion, a casing, upper and lower non-rotating grinding rings, an intermediate rotating ring, upper and lower annular series of grinding elements disposed between and engaging respectively the upper and intermediate rings and the intermediate and lower rings, said casing including a bed plate having a flange extending into the casing, the lower ring having an overhanging flange seated on the bed plate flange, bolts secured to said flanges and extending through the upper ring and outwardly of the grinding elements, said bolts providing a connection between the non-rotating rings, compression springs carried by said bolts and operative against the upper ring, and means for driving the rotating ring.

13. A pulverizer mill comprising, in combination, a casing including a bed plate provided with a flange extending into the casing, and a grinding assembly carried by said flange, said grinding assembly including a lower ring seating on said flange, a rotating ring, and an annular series of grinding elements arranged between and engaging against the lower and rotating rings, bolts secured to the lower ring and extending upwardly within the casing, and compression springs carried by said bolts operative to exert grinding pressure on the grinding elements, the outer diameter of the lower ring being less than the inner diameter of the casing whereby the grinding assembly may be lifted from said bed plate flange through the medium of the compression bolts.

14. A pulverizer mill comprising, in combination, a vertically arranged casing having an inwardly directed shelf, a grinding assembly disposed within the casing and including upper and lower non-rotating grinding rings, an intermediate rotating grinding ring, upper and lower annular series of grinding elements disposed between and engaging respectively the upper and intermediate rings and the intermediate and lower rings, and means wholly contained within the casing for exerting yielding grinding pressure on the grinding elements and for securing the rings and elements together as a self-contained assembly-unit, means including the shelf providing a support within the casing for the lower non-rotating ring and hence for the grinding assembly, from which support the grinding assembly may be raised as a unit, and means for driving said rotating ring.

15. A pulverizer mill comprising, in combination, a vertically arranged casing having an inwardly directed shelf, a grinding assembly disposed within the casing and including upper and lower non-rotating grinding rings, an intermediate rotating grinding ring, upper and lower annular series of grinding elements disposed between and engaging respectively the upper and intermediate rings and the intermediate and lower rings, and means wholly contained within the casing for exerting yielding grinding pressure on the grinding elements and for securing the rings and elements together as a self-contained assembly unit, means including the shelf providing a support within the casing for the lower non-rotating grinding ring and hence for the grinding assembly, releasable means for securing the lower non-rotating grinding ring to the shelf, and means for driving said rotating grinding ring.

16. A pulverizer mill comprising, in combination, a vertically arranged casing having an inwardly directed shelf, a grinding assembly including upper and lower non-rotating grinding rings, of which the lower ring is provided with a

peripheral extension, an intermediate rotating grinding ring, upper and lower annular series of grinding elements disposed between and engaging respectively the upper and intermediate rings and the intermediate and lower rings, and means wholly contained within the casing for exerting yielding grinding pressure on the grinding elements and for securing the rings and elements together as an assembly unit, means including the shelf providing a support within the casing for the lower non-rotating grinding ring and hence for the grinding assembly, and from which support the grinding assembly may be raised as a unit, said pressure-exerting and securing means including vertically arranged spring-carrying bolts, the lower ends of which are fixedly secured to said peripheral extension of the lower non-rotating grinding ring and the upper portions of which extend through the peripheral portion of the upper non-rotating grinding ring, and means for driving said rotating grinding ring.

17. A pulverizer mill comprising, in combination, a vertically arranged casing having an inwardly directed shelf, a grinding assembly including upper and lower non-rotating grinding rings, of which the lower ring is provided with a peripheral extension, an intermediate rotating grinding ring, upper and lower annular series of grinding elements disposed between and engaging respectively the upper and intermediate rings and the intermediate and lower rings, and means for exerting yielding grinding pressure on the grinding elements and for securing the rings and elements together as an assembly unit, means including the shelf providing a support within the casing for the lower non-rotating grinding ring and hence for the grinding assembly, and from which support the grinding assembly may be raised as a unit releasable means for securing the lower non-rotating grinding ring to the support, said pressure-exerting means including vertically arranged spring-carrying bolts, the lower ends of which are fixedly secured to said peripheral extension of the lower non-rotating grinding ring and the upper portions of which extend through the peripheral portion of the upper non-rotating grinding ring, and springs carried by said bolts operative against the upper side of the upper non-rotating grinding ring, means for directing material to be pulverized to the inner side of the grinding elements of the upper series and for discharging the pulverized material from the inner side of the grinding elements of the lower series, and means for driving the rotating grinding ring.

18. A pulverizer mill comprising, in combination, a casing, a shelf ring arranged within the casing, means in the casing providing a seat for the shelf ring, from which the ring may be raised, a grinding assembly disposed within the casing and including a non-rotating ring arranged at a substantially lower level than said shelf ring, an annular series of grinding elements supported thereon, an upper rotating ring supported on said grinding elements and means carried by said shelf ring for exerting yielding grinding pressure on said grinding elements and for securing said rings and elements together as a self-contained assembly unit, and means within the casing and extending between the shelf and lower rings for supporting the lower ring from said shelf ring.

HARRY R. COLLINS.
